UNITED STATES PATENT OFFICE.

LUCIEN BIVA, OF BROOKLYN, NEW YORK, ASSIGNOR TO PENNSYLVANIA TEXTILE MILLS, INC., OF CLIFTON, NEW JERSEY, A CORPORATION OF NEW JERSEY.

DESIGN FOR A TEXTILE FABRIC.

Application filed February 9, 1928. Serial No. 25,330. Term of patent 3½ years.

To all whom it may concern:

Be it known that I, LUCIEN BIVA, a citizen of France, residing in Brooklyn, county of Kings, State of New York, whose post office address is No. 295 Fifth Ave., city, county, and State of New York, have invented a new, original, and ornamental Design for a Textile Fabric, of which the following is a specification, reference being had to the accompanying drawing, forming part thereof.

The figure is a plan view of a textile fabric showing my new design.

I claim:

The ornamental design for a textile fabric substantially as shown.

LUCIEN BIVA.
